H. O. RUSSELL ET AL

TRIGGER MOTOR

Filed March 2, 1922

Inventor

H. O. Russell
C. L. Paulus

By Robert Heyman

Attorney

UNITED STATES PATENT OFFICE.

HERBERT O. RUSSELL, OF DETROIT, MICHIGAN, AND CHARLES LEIGH PAULUS, OF DAYTON, OHIO.

TRIGGER MOTOR.

Application filed March 2, 1922. Serial No. 540,508.

To all whom it may concern:

Be it known that we, HERBERT O. RUSSELL and CHARLES LEIGH PAULUS, citizens of the United States, residing, respectively, at Detroit and Dayton, in the counties of Wayne and Montgomery and States of Michigan and Ohio, have invented certain new and useful Improvements in Trigger Motors, of which the following is a specification.

- 10 This invention relates to trigger motors particularly adapted for use upon a Browning gun and operated by a pull upon the flexible cable encased in a semi-flexible metal casing.
- 15 The object of the invention is to produce a simple, practical and reliable trigger motor for use on the Browning gun operated by the "Type A" method of synchronizing the shots of a machine gun with the propeller 20 of an airplane.

With the above and other objects in view, the invention consists in the novel construction, combination and arrangement herein fully described, illustrated and claimed.

25 In the accompanying drawings:

- Figure 1 is a vertical longitudinal section through the improved trigger motor.
- Figure 2 is a plan view thereof.
- Figure 3 is an end elevation thereof.
- 20 Figure 4 is an end elevation taken from the opposite end of the trigger motor.

The improved trigger motor comprises a housing 1 having a base 2 and securing means 3 for fastening the housing in position. Mounted for reciprocatory movement longitudinally of the housing is a plunger 4 having a reduced shank or stem 5 around which is placed a coiled retracting spring 6 which serves to return the plunger 4 to its 40 normal position after it has been drawn outwardly by the impulse cable, the extremity of which is held in an end socket 7 in the plunger 4.

Operating substantially at a right angle to the plunger 4 is a sear slide 8 which is adapted to be reciprocated by the plunger 4 and which is retracted to its inward position by means of a spring 9 interposed between a fixed shoulder 10 in the housing and extension or shoulder 11 on the sear slide. The plunger 4 is formed with a cam face 12 which cooperates with a corresponding cam face 13 on the inner end of the sear slide.

In operation, the plunger 4 is pulled outwardly by the impulse cable which is con-

nected with any suitable impulse generator. In the outward movement of the plunger 4, the latter cams against the sear slide 8 and thrusts the latter outwardly thereby tripping the trigger of the machine gun (not shown) in the connection with which the trigger motor is used.

The mechanism above described also has the advantage that by means thereof a single shot may be fired.

Having thus described our invention, we claim:

1. In a trigger motor for machine guns, a trigger motor housing an impulse cable operated plunger slidable in said housing, a recess in said plunger having one of its walls inclined, and a sear slide adapted to be operated by said plunger, said sear slide having a portion provided with an inclined surface and adapted to extend into said recess. 75

2. In a trigger motor for machine guns, a trigger motor housing an impulse cable operated plunger slidable in said housing, a recess in said plunger having one of its walls inclined, and a sear slide adapted to be operated by said plunger in a direction substantially at right angles thereto, said sear slide having a portion provided with an inclined surface and adapted to extend into said recess. 80

3. In a trigger motor for machine guns, a trigger motor housing an impulse cable operated plunger slidable in said housing, a recess in said plunger having one of its walls inclined, and a sear slide adapted to be operated by said plunger in a direction substantially at right angles thereto, said sear slide having a portion provided with an inclined surface and adapted to extend into said recess, said plunger and said slide being provided with yieldable means for returning the same to their normal positions. 90

4. In a trigger motor for machine guns, a trigger motor having an impulse cable operated plunger slidable in said housing, a recess in said plunger having one of its walls inclined, and a sear slide adapted to be operated by said plunger, said sear slide having a portion provided with an inclined surface and adapted to extend into said recess, said slide being further provided with a shoulder having a surface parallel to and in slidable engagement with said plunger. 100

5. In a trigger motor for machine guns, a trigger motor having an impulse cable oper- 110

ated plunger slidable in said housing, a recess in said plunger having one of its walls inclined, and a sear slide adapted to be operated by said plunger, said sear slide having a portion provided with an inclined surface and adapted to extend into said recess, said slide being further provided with a shoulder having a surface parallel to and in slidable engagement with said plunger,

yieldable means between said shoulder and 10 said housing and between said plunger and said housing for retaining said slide and said plunger in their normal positions.

In testimony whereof we affix our signatures.

HERBERT O. RUSSELL.
CHARLES LEIGH PAULUS.
